(57) **CLAIM**

The ornamental design for a surgical rongeur, as shown and described.

DESCRIPTION

FIG. 1 is a side view of a first embodiment of a surgical rongeur showing my new design;

FIG. 2 is an enlarged perspective view of the surgical rongeur, taken along the line 2-2 of FIG. 1;

FIG. 3 is a side view of a second embodiment of a surgical rongeur showing my new design;

FIG. 4 is an enlarged perspective view of the surgical rongeur, taken along the line 4-4 of FIG. 3;

FIG. 5 is a side view of a third embodiment of a surgical rongeur showing my new design; and,

FIG. 6 is an enlarged perspective view of the surgical rongeur, taken along the line 6-6 of FIG. 5.
